(57) **CLAIM**

The ornamental design for a cordless drill, as shown and described.

DESCRIPTION

FIG. 1: is a right side elevation view of a cordless drill embodying my new design;

FIG. 2: is a left side elevation view thereof;

FIG. 3: is a front and left side perspective view thereof;

FIG. 4: is a rear elevation view of thereof;

FIG. 5: is a front elevation view of thereof;

FIG. 6: is a bottom plan view of thereof; and,

FIG. 7: is a top plan view thereof.

The broken lines in the drawings illustrate portions of the cordless drill that form no part of the claimed design.
